SANDBLAST TURNTABLE

Glenn A. Stearman, Enid, Okla., assignor to Stearman Aviation, Inc., Enid, Okla., a corporation of Oklahoma

Application July 14, 1943, Serial No. 494,727

4 Claims. (Cl. 51—15)

This invention relates to new and useful improvements in the art of sandblasting objects and more particularly to a turntable upon which the article to be sandblasted or otherwise treated is supported.

An important object of the present invention is to provide a turntable for supporting articles to be treated whereon a number of article supports are located and each capable of rotating, to the end that as the turntable proper rotates, the individual articles to be sandblasted or otherwise treated are also rotated so that the workman can sandblast or otherwise treat the entire surface of an object without moving from a fixed position.

Another important object of the invention is to provide a turntable of the character stated which can be manipulated either from manual or powdered means and wherein means is provided permitting the turntable to be tilted when the need arises.

Other objects and advantages of the invention will become apparent to the reader of the following description.

In the drawings:

Figure 1 represents a top plan view of the powered form of turntable.

Figure 2 is a side elevational view with a portion in section, showing the form of the invention disposed in Figure 1.

Figure 3 is a fragmentary vertical sectional view through the central portion of the turntable.

Figure 4 is a fragmentary elevational view showing the means for rotating the individual article support.

Figure 5 is a fragmentary vertical sectional view through the upper portion of one of the individual article supports.

Figure 6 is a fragmentary top plan view of the manually operated form of the invention.

Referring to the drawings wherein like numerals designate like parts, it can be seen that numeral 5 generally refers to a supporting frame having end structures 6, 6, each provided with a bearing 7 at its upper portion. Numeral 8 denotes a bar-like swing or cradle member of substantial U-shape and having trunnions 9, 11 disposed through the bearings 7, 7. A handle or like member 12 depends from the journal 11 and is used for oscillating the swing member 8.

Rising from the intermediate portion of the swing member 8 is a neck 13, flanged at its upper end as at 14. Numeral 15 denotes a substantially large horizontally disposed wheel upon the central portion of which is located a

plate 16. Bolts 17 pass downwardly through the plate 16 and wheel 15 as well as the flange 14 and are equipped with nuts 18. Thus the wheel 15 is positively secured to the neck 13 and also has an upstanding stationary stub-shaft 19 which projects upwardly into a vertical sleeve 20 which is closed at its upper end as at 21. The lower end of this sleeve extends downwardly through an opening 22 in a turntable 23 and may be secured to or formed integral with a plate 24 which is secured to the underside of the turntable 23 by bolts 25.

Fulcrumed upon the trunnion 11, as shown in Figure 2, is a substantially diamond-shaped frame 26, the same being fulcrumed as at 27. A flexible shaft in a conduit 28 extends through this frame and the shaft is journaled through a bearing 29 to a drive roller 30 which rides a rim 31 at the periphery of the turntable 23. A brake block 32 is supported by the frame 26 just under the roller 30 by a bracket 33. A spring 34 is provided between the bracket 33 and the swing member 8, as shown in Figure 2, to serve to pull the roller 30 downwardly into driving engagement with the rim 31.

A cable or like member is attached to the eye end 35 of the frame 26, to the end that when desired, the frame 26 can be rocked, to lift the drive roller 30 and apply the block brake 32, in order to stop the rotation of the turntable.

It can be seen that individual article supports are generally referred to by numeral 36. Each support consists of a barrel 37 rising from the turntable 23 and downwardly through each barrel 37 is snugly disposed a shaft 38 equipped with a V-grooved wheel 39 at the lower end thereof. Adjacent the upper end of each shaft 38 is a collar 40 and through this collar and the corresponding portion of the shaft 38 above the barrel 37 is disposed a cross pin or bolt 41, which obviously rides the upper end of the barrel 37 as the shaft 38 rotates. Obviously, articles are disposed over the support 36 or in any way desired carried by the upper end of the shaft 38, so that they will rotate individually as the turntable 23 is rotated by the drive roller 30.

A V-shaped rim 42 is provided on the wheel 15 and this engages in the V-grooves of the wheels 39 and serves to rotate these wheels and their corresponding article supporting shafts 38.

A modification of the invention is shown in Figure 6 and this represents a manually operated mechanism. In this form of the invention the reference character 5a denotes a frame structure having end structures 6a equipped with bearings

1a through which the trunnions 11a are disposed. These trunnions 11a being located at the ends of a swing member 8a which supports a turntable 23a in the manner that the swing member 8 and associated mechanism shown in Figure 3 supports the turntable 23.

In this modified form of the invention an arm 45 supports a rocker 46 and a cable 47 disposed over one or more pulleys 48 extend through the trunnion 11a, which is hollow, and connects to one end of the bellcrank 46. The other end of the bellcrank 46 is connected by a spring 49 to an arm 50 projecting from the trunnion 11a and this same end of the bellcrank 46 is provided with a pivotal pusher element 51 for engaging teeth 52 at the periphery of the turntable 23a.

The cable 47 may extend to a crank 53 at one end of an elongated shaft 54 equipped with a treadle 55. Obviously, a pull on the cable 47 will rock the bellcrank 46 and exert a push on the pusher element 51 which will effect a movement to the turntable 23a. Continual operation of the cable 47 will maintain the turntable 23 rotating.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. Apparatus of the character described comprising a rotatably mounted turntable, article supports on the turntable and means for driving the turntable, said drive means comprising a rockable frame, a shaft extending into the frame and provided with a drive roller for engaging a peripheral portion of the turntable and means for rocking the frame upwardly to disengage the roller, and a brake element carried by the rockable frame for engaging a peripheral portion of the turntable to stop the same when the roller has been moved to disengaged position.

2. Apparatus of the character described comprising a turntable mounted for swinging movement about an horizontal axis and rotatable about an axis perpendicular to the axis of swing-

ing movement thereof, article supports on the turntable and means for driving the turntable, said article supports each consisting of a vertical barrel, a rotary shaft disposed vertically through the barrel and having a portion at its upper end projecting above the barrel, each of the vertical shafts being provided with a wheel at its lower end, and a wheel-like support for the turntable in driving engagement with the wheels of the vertical shaft.

3. In apparatus of the class described, a U-shaped cradle member having end trunnions rotatably mounted to rock about an horizontal axis whereby said member is swingable laterally, an upstanding member in the center of the cradle member, a wheel fast on said upstanding member, a turntable rotatably mounted on said wheel to be driven relative to the same, article supporting members on said turntable rotatably mounted in the turntable, friction drives between said article supporting members and wheel whereby said article supporting members are rotatable about axes under rotation of the turntable relative to the wheel, and means to rotate said turntable mounted on said cradle member to swing therewith.

4. In apparatus of the class described, a U-shaped cradle member having end trunnions rotatably mounted to rock about an horizontal axis whereby said member is swingable laterally, an upstanding member in the center of the cradle member, a wheel fast on said upstanding member, a turntable rotatably mounted on said wheel to be driven relative to the same, article supporting members on said turntable rotatably mounted in the turntable, friction drives between said article supporting members and wheel whereby said article supporting members are rotatable about axes under rotation of the turntable relative to the wheel, and means to rotate said turntable mounted on said cradle member to swing therewith comprising a spring loaded frame vertically swingable in opposite directions, respectively, on said cradle member, coacting friction drive devices on said frame and turntable, respectively, rendered ineffective by swinging of said frame in one direction, and brake means on said frame operative against said turntable under swinging of said frame in said one direction.

GLENN A. STEARMAN.
